Attorney

UNITED STATES PATENT OFFICE

WILLIAM P. SAYLOR, OF PITTSBURGH, PENNSYLVANIA

FASTENER

Application filed February 23, 1929. Serial No. 342,157.

The present invention appertains to improvements in a fastener for garment supporters.

The principal object of this invention is to provide a fastener for garters which will permit the positive attachment of the hose to the garter.

Another important object of the invention is based upon the fact that the most expensive portion of this type of garter is the tab member, which in the present invention has its plate portion molded from a single piece of material to which a metallic clasp may be readily assembled in completing the tab member for use.

Another important object of the invention is to provide a simple and efficient tab member which will not only be exceedingly durable in use, but which because of its unusual construction, will permit of the rapid attachment or detachment of the sock with respect thereto as well as the rapid attachment or detachment of the leg encircling strap with respect to the tab.

These and other objects of the invention will become more apparent to the reader after considering the invention as described and claimed hereinafter.

In the drawing:—

Figure 1 represents a front elevation of the invention in its entirety.

Fig. 2 is a vertical sectional view taken substantially on the line 2—2 of Fig. 1.

Fig. 3 is a horizontal sectional view taken substantially on the line 3—3 of Fig. 1.

Fig. 4 is a perspective view of a loop connection between the limb encircling strap and the tab plate.

Referring to the drawings, wherein like numerals designate like parts, the invention consists of a tab member generally referred to by the numeral 3. This tab member is constructed of two parts, namely the plate 4, and the clasp arm 5.

The plate 4 by a suitable process of molding, is formed in a manner to provide the necessary adjuncts whereby the limb encircling strap 6 and the clasp arm 5 may be readily connected without the necessity of attaching any additional securing means to

the plate. The tab member, as a finished article, consists of an elongated plate of any suitable moldable material, such as celluloid, bakelite, or some other non-metallic substance.

The plate is reduced at one end portion and formed to provide at this end, a protuberance 7 having its side walls cut inwardly in the manner shown in Fig. 3, to provide recesses 8. The plate at its intermediacy is provided with a projection 9 formed with an aperture 10. The enlarged end portion of the plate is formed so as to provide a pair of transversely spaced and headed studs 11.

Thus the plate is formed to provide the necessary adjunct whereby the ends of the limb encircling strap 6 may be detachably connected thereto while the hose engaging clamp arm 5 may be engaged with the projection 9, in the manner shown in Fig. 2.

Each end of the limb encircling strap 6, which is preferably of some suitable elastic material, is equipped with a triangular shaped member 12 having its apex portion 13 extended outwardly, to provide a bight engageable under one of the headed studs 11, of the plate 4.

The clasp arm 5 is the only point of the tab member constructed of metal and this consists of an elongated strip of a springy metal provided with a loop 14 at one end for pivotal engagement with the apertured projection 9 on the plate 4. The arm is provided adjacent its opposite end with a pair of laterally disposed fingers 15—15, which are curved inwardly beyond one side of the arm and rolled outwardly at their free ends 16.

These spring fingers are adapted for tensile engagement within the recesses 8 of the protuberances 7 in the manner substantially shown in Figs. 2 and 3 respectively.

It is contended that the present article can be manufactured at a cost at least as reasonable as the types of garters of this character now on the market, while possessing far more appealing advantages than the conventional variety. It is also to be understood that certain changes in the specific

shape, size, and materials may be resorted to in the construction of this novelty, without departing from the spirit and scope of the invention as claimed hereinafter.

Having thus described my invention, what

5 I claim as new is:—

In a hose supporter, a plate to which the usual limb encircling strap may be secured, an arm pivotally secured at one end to said plate, the opposite end of said arm being provided with a pair of laterally disposed and converging spring fingers, a protuberance on the said plate, said protuberance being provided with a pair of pockets therein, into each of which one of the fingers is adapted to engage, said arm at the free end thereof being provided with an extension for engagement by a finger of the person operating the arm, said extension being curved in the direction of the plate.

20 In testimony whereof I affix my signature.

WILLIAM P. SAYLOR.
